Harold W. Glascock, Jr., and Walter J. S. Byford,
Fort Jackson, S. C., and Walter R. Byford,
Elmwood, N. C.

Application February 28, 1942, Serial No. 106,036

Term of patent 7 years

To all whom it may concern:

Be it known that Harold W. Glascock, Jr., a citizen of the United States of America and residing at Fort Jackson, county of Richland, State of South Carolina; Walter J. S. Byford, a citizen of the United States of America and residing at Fort Jackson, county of Richland, State of South Carolina; and Walter R. Byford, a citizen of the United States of America and residing at Elmwood, county of Iredell, State of North Carolina, have invented a new, original, and ornamental Design for a Medical Field Trailer, of which the following is a specification, reference being had to the accompanying drawings, forming a part thereof.

Figure 3 is a perspective view of the rear and left hand side, showing the trailer as it appears with the rear and side door panels in lowered position, the drawer locking bar members removed and several drawers in extended position;

Figure 4 is a perspective view of the rear and right hand side showing the trailer as it appears with the rear door panel in lowered position, the drawer locking bar members removed, and several drawers in extended position.

We claim:

The ornamental design for a medical field trailer, substantially as shown.
